Horace C. Handee,
Attorney

UNITED STATES PATENT OFFICE

GEORGE E. EVEY, OF TORRANCE, CALIFORNIA

PLIERS

Application filed February 5, 1931. Serial No. 513,680.

This invention relates to new and useful improvements in tools, and particularly to pliers of the adjustable type.

In the common pliers, wherein one of the members is formed with a transverse slot, terminating in circular portions, for the purpose of shifting the members so as to change the position of the pivot, and thereby cause the jaws to be separated for different distances, to permit gripping large or small work, the portion of the slot, intermediate the ends, becomes worn, with the result that the members will not remain in their narrow separated adjustment, and the discarding of the pliers.

The principal object of the present invention is to provide pliers of this type, which are so constructed, with relation to the adjustable pivot connection, that the pivot may be shifted from one place to another, and accomplish its intended function, without slipping, and without the disadvantage above mentioned.

Another object is to so arrange the slot so that whether or not the walls thereof become worn, so as to widen said slot, the adjustment of the pivoted members of the pliers will properly function in any of their adjusted positions.

Another object is to provide pliers of the adjustable type wherein the pivoted members are capable of adjustment to cause the jaws to move longitudinally of each other, for the purpose of reducing the size of the notched opening between said jaws, whereby to permit grasping very small objects.

Other objects and advantages will be apparent from the following description when taken in connection with the accompanying drawing.

In the drawing:

Figure 1 is an elevation of a pair of pliers, made in accordance with the present invention, in position for gripping medium sized work.

Figure 2 is an elevation of the pliers, in position for gripping very small work.

Figure 3 is a perspective view of the pivot bolt.

Referring to the accompanying drawing,

10 and 11 represent a pair of plier members, each having a handle shank 12. The member 10 includes a pivotal portion 13, which is slightly enlarged, as shown, and as is usual in this type of pliers, such portion is formed with the jaw 14.

The member 11 includes an enlarged portion 16, with an outer terminal jaw 16', for cooperation with the jaw 14, for gripping work. In the portion 16 there is formed an approximate T-shaped slot, including the head portion 32 and the curved leg portion 35, connected intermediately with the head portion 32. In the outer ends of the head portion 32 there are formed the circular portions 33 and 34, while in the outer extremity of the leg portion 35 there is formed a similar circular portion 36.

The pivot member of the pliers, for connecting the members, and permitting the different adjustments, consists of a bolt, designated, as a whole by the numeral 24, and including a shank having three portions, an outer threaded end portion 25, and intermediate portion 26 angular in cross section, and the inner end portion 27, the latter having two opposite flat faces 28, and the two opposite outwardly curved or bowed faces 29, forming parts of a complete circle, which permits free rotation within the said circular portions of the T-shaped slot, while the flat faces permit sliding of the bolt through the portions of the slot, between the said circular portions. On the last-named end of the bolt 24 is a head 36, which bears on the outer wide face of the portion 16, of the member 11, as shown in the drawing. The angular portion 26, of the bolt, is disposed in an angular opening in the member 10 to prevent rotation of the bolt therewithin, while the threaded end of the bolt projects beyond the outer wide face of the portion 13, of the member 10, to receive a nut thereon, whereby to hold the bolt against rotation, and maintain the pivoted members 10 and 11 in proper sliding contact with each other.

When the parts are in the position shown in Figure 1, the pivot bolt lies within the circular portion 34, of the slot 17, whereby the jaws of the pliers will grip comparative-

ly work of ordinary size, the rounded faces 29, of the pivot bolt 24 permitting the free pivotal movement of the members 10 and 11 thereon. To adjust the pliers for large work, 5 the operator holds the shank of the member 11, swings the member 10 until it lies at approximately right angles to the member 10, moves the member 10 toward the left, so as to cause the pivot bolt 24 to slide in the leg portion 35, of the slot, until the bolt lies within the circular portion 36. Pivotal movement 10 of the members 10 and 11, may now be accomplished, the jaws 14 and 16' spaced a greater distance apart, so that they may grip 15 work of greater diameter.

The pliers are also adapted for gripping work of smaller diameter than can be gripped, when adjusted into the position of Figure 1, such adjustment being clearly shown in Figure 2, wherein the jaw 16' lies inwardly from 20 the jaw 14.

Attention is particularly called to the fact 25 that the portion 35, of the T-shaped slot, is slightly curved in the direction of the handle portion of the member 11, and that such portion extends transversely of said member, whereby the circular terminal 36 lies in the same plane as the circular portion 34, of the 30 part 32, so that the jaws 14 and 16 will properly engage each other, in either of their adjustments toward and away from each other.

It is to be particularly noted that the circular 35 end portions of the slot parts are located remote from the junctures of such portions with the elongated parts, so that the pivot bears against the circular walls of said circular portions, thereby preventing any 40 wear on the ends of the side walls of the elongated slot parts, at the said junctures.

In the present device, even should the 45 straight portions of the slot become widened, by wear, the members of the pliers will operate properly, no matter in what position they have been adjusted, as the wear, during the pivotal movement of the members is wholly within the circular portions of the slot.

What is claimed is:

1. Adjustable pliers comprising a pair of crossed pivoted members having terminal 50 cooperating jaws, one of the members having a longitudinal slot in its pivotal portion formed with a circular portion at each end, and a transverse slot having one end intersecting the longitudinal slot intermediately 55 and having a circular portion at its other end, and a pivot member on the pivotal portion of the other member having a head of greater width than said slots and circular 60 portions and movable in said slots to permit adjustment of said jaws toward and away from each other and longitudinally of each other, said pivot being rotatable in said circular portions.

2. Adjustable pliers comprising crossed 65 members having terminal jaws, one of said

members having a longitudinal slot and a transverse slot intersecting the longitudinal slot intermediately, a pivot carried by the other member slideable in said longitudinal slot to permit longitudinal movement of the members and the adjustment of said jaws past each other and slideable in the transverse slot to permit transverse movement of the members to adjust said jaws toward and away from each other, means in the ends of the longitudinal slot for engagement with the pivot to hold the members in adjusted position longitudinally past each other, means in the outer end of the other slot for engagement with the pivot to hold the members in adjusted positions toward and away from each other, and a head on said pivot of greater dimensions than said slots and said slot end means.

3. Adjustable pliers comprising crossed members having terminal cooperating jaws on their corresponding ends, one of said members having a longitudinal slot and a transverse slot intersecting the longitudinal slot intermediately, a pivot carried by the other member slideable in said longitudinal slot to permit longitudinal movement of the members and the adjustment of said jaws past each other and slideable in the transverse slot to permit transverse movement of the members to adjust said jaws toward and away from each other, enlargements in the ends of the longitudinal slot for engagement with the pivot for holding the members in adjusted positions longitudinally past each other, and an enlargement in the outer end of the other slot for engagement with said pivot for holding the members in adjusted positions toward and away from each other, said pivot having a terminal of greater width than the enlargements.

In testimony whereof, I affix my signature.
GEORGE E. EVEY.
